UNITED STATES PATENT OFFICE

2,429,793

ELECTRICAL RECEPTACLE

George B. Benander, Oaklawn, R. I., assignor to
Monowatt Electric Corporation, a corporation
of Connecticut

Original application March 24, 1943, Serial No.
480,348. Divided and this application Septem-
ber 8, 1945, Serial No. 615,135

5 Claims. (Cl. 173—328)

1

This application is a division of my application Serial No. 480,348, filed March 24, 1943, Electric connector.

The invention relates to electrical receptacles or sockets and has for its object to provide an improved construction and arrangement which is simple in structure, reliable in operation, and capable of being manufactured and assembled at low cost.

For a consideration of what I believe to be novel and my invention, attention is directed to the following specification and to the claims appended thereto.

In the drawing, Fig. 1 is a sectional view of a receptacle embodying my invention; Fig. 2 is a perspective view, partly broken away, of the receptacle; Fig. 3 is a perspective view of one of the contacts; Fig. 4 is a perspective view of the receptacle viewed from an angle different from that of Fig. 2, and Fig. 5 is a detail perspective view of a clamping ring.

Referring to the drawing, the receptacle comprises an insulating molded block 1 having a plurality of bores 2 and an insulating disk or cover 3 having bores 4 aligned with the bores 2. The block 1 and the disk 3 in accordance with my invention are secured together by means of a dove-tailed snapring 5 (Fig. 5) which has a cylindrical ring segment of about 180 angular degrees and opposed dovetailed projections 6, 7 extending axially from opposite sides of the segment at its ends. The insulating block 1 has a collar 8 spaced from its upper end and the disk 3 has a similar collar 9 spaced from its lower end. Thus, when the block 1 and the disk 3 are assembled there is defined between the collars 8 and 9 an outer circumferentially extending groove 10 for receiving the dovetailed snapring 5. The collars 8 and 9 are cut away to provide dovetailed recesses 10^a for receiving the dovetailed projections 6, 7 of the snapring. When inserted into these recesses the dovetailed snapring holds the block 1 and the disk 3 together.

Mounted in the bores 2, 4 are terminal contacts 11 held between shoulders 12 at the lower ends of bores 2 and the under side of disk 3, the contacts 11 being provided with struck-out tongues 12^a which engage the disk. Each contact 11 comprises a tube formed from sheet stock rolled into a cylinder, the seam between the edges being indicated at 13. At its upper end it is cut away to provide a recess 14 in which may be positioned and soldered the bared end of a conductor 15. The other end of the cylinder forms a socket 16 to receive a pin contact. Between the recess 14

2

and the socket 16 is a partition wall or dam 17 which serves to prevent solder from running down into the socket when a wire is being soldered in the recess. Partition wall or dam 17 is in the form of a short pin which is positioned in the contact and held by grooves or indentations 18 formed in the wall of the contact. Each contact has a notch 19 at its lower end which fits over a projection 20 at the lower end of bore 2 to position the contact circumferentially and prevent its turning.

In wiring the receptacle, the conductors 15 may be soldered or attached in other suitable manner in the recesses 14 of terminal contacts 11 after the contacts have been assembled in the receptacle housing. Or, the conductors may be attached to the terminal contacts prior to the contacts being assembled in the receptacle housing in which case the two parts 1 and 3 of the housing are first connected together after which the terminal contacts with the conductors attached are inserted into the bores of the housing, struck-out tongues 12^a yielding as the contacts are pushed into the bores and then springing out beneath the under side of disk 3 as shown in Fig. 2.

By my invention, I provide a structure which comprises a minimum of parts and which can be quickly assembled at low labor cost. In assembling the structure, it is necessary merely to drop the contacts in bores 2, position the disk or cover 3 over their outer protruding ends and put the snapring 5 in place.

What I claim as new and desire to secure by Letters Patent of the United States is:

35. 1. A receptacle for electrical connectors comprising a block having a plurality of bores enlarged at one end thereof, a disk engaging the block and having a plurality of bores in alignment with the first mentioned bores, means including a dovetailed snapring securing the disk to the block, a plurality of terminal contacts each disposed in a pair of aligned bores and having a lateral projection located in the enlarged end of the bore in the block and engaging the adjacent surface of the disk.

50. 2. A receptacle for electrical connectors comprising a block having a plurality of bores enlarged at one end thereof, a disk engaging the block and having a plurality of bores in alignment with the first mentioned bores, means including a dovetailed snapring securing the disk to the block, a plurality of terminal contacts each disposed in a pair of aligned bores and having a lateral projection located in the enlarged end of the bore in the block and engaging the adjacent

surface of the disk, and means for angularly positioning each terminal contact.

3. A receptacle for electrical connectors comprising a block, a disk engaging the block and forming therewith an outer circumferentially extending groove with axially extending dovetailed recesses, and a dovetailed snapring located in the groove and recesses for securing and angularly positioning the disk on the block.

4. A receptacle for electrical connectors comprising a block, a disk engaging the block and forming therewith an outer circumferentially extending groove with axially extending dovetailed recesses, and a dovetailed snapring located in the groove and recesses for securing and angularly positioning the disk on the block, the disk and block having a plurality of aligned bores, terminal contacts located in the aligned bores, and means including tongue and groove connections between the bores and the terminal contacts for axially and angularly positioning each contact in a pair of aligned bores.

15

20

5. A cylindrical member split into two parts along a plane perpendicular to its axis, said parts facing each other and having adjacent shouldered portions forming a groove with circumferentially spaced dovetailed recesses in each part, and a dovetailed segmental snapring disposed in said groove and recesses to secure the parts together.
